UNITED STATES PATENT OFFICE.

CHARLES J. KIRK, OF NEW CASTLE, PENNSYLVANIA.

HEAT-TREATING FURNACE.

1,332,501.

Specification of Letters Patent. Patented Mar. 2, 1920.

Application filed March 1, 1919. Serial No. 280,131.

To all whom it may concern:

Be it known that I, CHARLES J. KIRK, a citizen of the United States, a resident of New Castle, in the county of Lawrence and State of Pennsylvania, have invented a new and useful Improvement in Heat-Treating Furnaces; and I do hereby declare the following to be a full, clear, and exact description thereof.

10 My invention relates to a heat-treating furnace.

The invention has more special reference to that class of heat treating furnace in which the objects to be heated are not subjected directly to the hot products of combustion, but are subject to the indirect action of the heat, such as in the burning of pottery and in the annealing of metal.

15 The object of my invention is to provide a compact form of furnace of this character in which the objects to be treated may be moved continuously through the furnace on a double line of tracks. The cars on one track entering in the opposite direction from the other, provision being made for utilizing the heat emanating from the heated cars and the objects on one track for aiding in heating the objects entering the furnace from the opposite end on the other track, thereby conserving the heat and reducing the time required for treatment as well as the fuel consumed.

20 To these ends my invention comprises the novel features hereinafter set forth and claimed.

In the accompanying drawing Figure 1 is a plan view partly in section of my improved furnace; Fig. 2 is a longitudinal section, and Fig. 3 is an enlarged cross-section on the line 3—3 Fig. 1.

25 In the drawing the numeral 2 designates a suitable base or foundation upon which the furnace is erected, said furnace consisting of the side walls 3 and the top or crown 4.

The heating chamber 5 is divided into two compartments by the partition wall 6, which also aids to strengthen and support the roof 4. This partition wall 6 is provided with the openings 7 arranged at intervals at the top and bottom and preferably staggered with relation to each other.

30 Suitable combustion chambers 8 and 9 are provided at each side of the furnace for supplying the heat whether gaseous or solid fuel is employed. These furnaces may be

of any suitable construction and I have only illustrated them in a diagrammatic form in Fig. 1.

Communicating with the combustion chambers 8 and 9 are the flues 10 and 11 respectively in the side walls of the furnace. The flues 10 communicate with each other through the flue 12 which passes over the top of the furnace chamber 5, and the flues 15 communicate through a like flue 13.

These flues 10 and 11 are non-communicative, being separated from each other by the wall 14. Outlet flues 15 and 16 are provided for the flues 10 and 11 respectively.

Within the heating chamber are the tracks 17 and 18 upon which the cars 19 and 20 travel respectively, said cars being made up of suitable refractory material to withstand the high heat to which they are subjected in passing through the furnace. The objects 21 to be treated are arranged upon said cars so as to allow the heat to circulate in and around the same during their passage through the furnace.

35 The ends of the furnace are provided with suitable doors 22.

In the operation of the furnace the ware mounted on the cars 19 is introduced into the furnace at one end and the ware mounted on the cars 20 is introduced on the opposite track at the other end of the furnace. The heat from the combustion chambers 8 and 9 passes through the flues 10 and 11 and also by the flues 12 and 13 to the flues 15 at the opposite side. The cars and the ware as they pass through the heating chamber are heated to a high temperature, getting hotter as they near the discharge end. Accordingly the heat given off by said highly heated cars and the objects carried thereon will pass through the openings 7 in the partition 6, and said heat is employed for assisting in the heating of the cold cars which are coming in on the next track in the next compartment of the heating chamber. These cold cars being cooler chill the air and it drops to the bottom openings in partition wall 6, and passes up through the heated cars on the opposite track and being heated thereby ascends and escapes through the upper openings 7, thereby creating a circulation as indicated by the arrows.

40 In this manner I make use of the heat given off by the outgoing cars to heat the incoming cars, and thereby create a saving and a consequent reduction in the amount of

fuel. Furthermore by this construction the length of the furnace may be reduced as the heating is accomplished in a shorter space of time and consequently such a long furnace is not required. It will, of course, be understood that as one car passes out at the discharge end a new car is admitted to the receiving end, so that the process is a continuous one, and it is not necessary to allow the furnace to cool down for charging and re-charging.

What I claim is:

1. In a heat-treating furnace having a heating chamber, a longitudinal partition wall having openings therein dividing said chamber into two communicating compartments, heating flues formed in the walls of said furnace, one set of flues for one section of the furnace and the other set for the other section, said sets of flues being non-communicating, and means for supplying heat to said flues.

2. In a heat-treating furnace, having a heating chamber, a longitudinal partition wall having openings therein dividing said heating chamber into two communicating compartments, heating flues formed in the side walls of said furnace, one set of flues for one section of the furnace and a like set of flues for the other section of the furnace, said sets of flues being non-communicating, cross-over flues connecting said flues, and means for supplying heat to said flues.

3. In a heat-treating furnace, having a heating chamber, a longitudinal partition wall having openings therein dividing said heating chamber into two communicating compartments, flues formed in the side walls of said furnace, one set of flues for one section of said furnace, and another set for the other section of said furnace, said sets of flues being non-communicating, and a combustion chamber at each side of said furnace communicating with said flues.

4. In a heat-treating furnace, having a heating chamber, a longitudinal partition wall dividing said chamber into two compartments, and said partition having openings at its upper and lower portions, whereby the heat emanating from the heated bodies introduced at one end of said furnace into one compartment rises and passes through said upper openings into the other compartment while the air chilled by the cooler bodies introduced at the other end of said furnace in said other compartment descends and passes through said lower openings back into the first named compartment creating a circulation.

In testimony whereof I the said CHARLES J. KIRK have hereunto set my hand.

CHARLES J. KIRK.
